UNITED STATES PATENT OFFICE.

ARTHUR SPILLING, OF CASSEL, GERMANY.

SOCIETY GAME.

Application filed July 7, 1927, Serial No. 204,008, and in Germany April 14, 1927.

This invention relates to a society game pertaining to that class of such games in which counters or men are moved along on certain paths provided on a draught-board or disk, the length of the individual draughts being determined by the number of the points of dice, as well as by certain rules. The improved game forming the subject-matter of this invention is illustrated diagrammatically and by way of example in the accompanying drawing which shows the game in plan. The playing ground proper is circular, and divided into four concentric rings designated I, II, III and IV and being, preferably differently colored. The details are as follows:

There are in the rings I, II and III thin circular lines, as well as circular and star-shaped fields connected by these lines. The counters or men are to be moved along the thin lines from field to field in counter-clockwise direction, as indicated by arrows. The three concentric lines in the ring III, or, more precisely, the fields located in these lines, are connected with each other by radial lines, and some of these latter extend through the ring II into the ring I, these extensions forming paths on which the counters or men can pass from one ring to another one.

Every playmate receives five counters or men. It is, in the example shown in the drawing, assumed that the game is intended for four playmates, and there are provided for them, or, more precisely, for their counters or men, four groups of fields located in the ring II and consisting each of one large circle and five small ones. The counters or men are to be put on the small rings. The groups are numbered 1, 2, 3 and 4, and groups of five fields or circles 1, 2, 3 and 4, but of larger diameter, are provided also in the ring IV. The groups are, preferably, distinguished also by different colors, for instance in this manner: 1=red, 2=green, 3=blue, and 4=yellow. The colors of the rings may, for instance, be as follows: I=yellow, II=blue, III=red, and IV=black. The fields in the ring II, that is to say, the smaller circles of those fields, are connected by radial lines with circles of the same size located in the ring III and bearing also the numbers, or

the colors, or both, corresponding to the fields in the ring II. The small circles in this ring are those upon which each playmate places his counters or men.

Between the radial lines connecting the rings I with each other, as well as the rings 2, 3 and 4, and extending from the ring II through the ring III, are radial lines extending from the ring I through the ring II into the ring III and being beset with star-shaped fields. These radial lines are called "fortune" lines and permit transposing the counters or men from one of the three rings mentioned to any other of them. There are four star-shaped fields in the ring I, four in the ring II, and twelve in the ring III, and between every two star-shaped fields of the ring I are five point-shaped fields, as shown; and as regards the ring II, there are between every two star-shaped fields four point-shaped fields and a group of six fields consisting each of five small circles and one larger one, as already described. The fields forming these groups are merely starting fields, not playing fields, except, however, the larger circles pertaining to them.

The object of the play is to transpose or shift the five counters or men assembled in any one of the starting field groups through the ring III onto the corresponding five large circles in the ring IV, that transposing or shifting being, however, to be effected in a certain manner corresponding to certain playing rules, as dealt with hereinafter.

Generally two dice are used, and two counters or men are moved after each throw, and each of them is shifted over as many path portions as are shown by the appertaining die. Summing up the points and moving only one counter or man over a corresponding number of path portions is forbidden. The counters or men are shifted onto fields in the outermost annular line of the ring III. Each counter or man must pass over the entire length of said line until it arrives again at the circle from which it had started in the said line, and having arrived thereon it is permitted to be shifted at once onto the neighboring circle in the next or middle annular line in which it then proceeds in the

same manner, the only difference being that two points are added at every throw to the number of the points thrown in order to accelerate the play. When the counters or men have made their way also through the middle annular line and arrive also in it at the starting circle they can be shifted over at once onto the third or inner annular line in which then three points are added to those thrown at every throw, the reason for this addition being also in this case to accelerate the play, that is to say, to accelerate it still more than in the ring II. At the end of the path in the inner annular line in the ring III the counters or men pass over onto the large circles located in the ring IV. Of course, each counter or man is not permitted to get over onto any other color, as regards said large circles in the ring III, than that which it bears itself. It may be that a counter or man when having arrived at the end of its path in the said annular line must be shoved to and fro until the number of the points of the die thrown is just that necessary for the purpose in view.

There are, however, exceptions of the above rules, viz., exceptions caused by lucky chances. If, for instance, a counter or man shoved along upon the outer annular line of the ring III gets onto a star-shaped field it is permitted to pass over at once to the inner line without passing through the entire length of the outer line and the middle one. And if a counter or man running along upon the middle annular line gets onto a star-shaped field it can instantly pass over to the inner line. Furthermore, if a counter or man meets on its way another counter or man of another color, this other counter or man must give way and get radially outwards, either from the inner or the middle line of the ring III into the outer line thereof, or further outwards into the ring II or even into the ring I, but never as far back as to re-enter any one of the appertaining starting circles, i. e. circles bearing the same color as the respective counter or man; but in the ring I that counter or man may move to one or the other side.

If in the middle annular line of the ring III a counter or man meets a counter or man bearing another color and located lefthand from it, the owner of the first-mentioned counter or man is entitled to exchange the two counters or men, and if the same thing should occur, by way of chance, in the other line where there has been the counter or man met with, that is to say, if also in this other line a counter or man of another color should lie lefthand from that newly arrived, another exchange of the two counters or men concerned may take place.

Exchanges can take place also between the rings I and II, as well as between the rings II and III, but only if the counters or men

bearing two colors stand side by side on a radial line with fields of large circles or on a radial line with star-shaped fields.

The thin lines indicate the ways or paths on which the counters or men are to be shifted or transposed.

That playmate is the victor who is the first whose counters or men have arrived on the five large circles in the ring IV. The play is rendered particularly animating and stimulating for the reason that each playmate has continually his or her five counters or men in the combat, and this being so, not only luck, but also cleverness is required to be victorious.

I claim:

1. A society game, comprising a board showing four concentric rings, an annular line in each of the outer two rings and three annular lines in the third ring, counter- or men-fields inserted into all said lines, separate fields located in the fourth or innermost ring and radial lines connecting some of the fields in one ring with some of the fields in another ring.

2. A society game, comprising a board showing four concentric rings, an annular line in each of the two outer rings and three annular lines in the third ring, counter- or men-fields inserted into all said lines, separate fields located in the fourth or innermost ring and radial lines connecting some of the fields in one ring with some of the fields in another ring, said fields being divided into groups, each of which is intended for one of the playmates, substantially and for the purpose set forth.

3. A society game, comprising a board showing four concentric rings, an annular line in the outermost ring, an annular line also in the next ring, and three annular lines in the third ring; counter- or men-fields inserted into all said rings, separate groups of fields in the second ring, separate fields located in the fourth or innermost ring, radial lines connecting some of the fields in one ring with some of the fields in another ring and extending from the outermost ring to the separate fields in the innermost one, the fields connected by said radial lines being larger than the other ones.

4. A society game, comprising a board showing four concentric rings, an annular line in each of the two outer rings and three annular lines in the third ring, counter- or men-fields inserted into all said lines, separate fields located in the fourth or innermost ring, equally distributed radial lines connecting some of the fields in one ring with some of the fields in another ring and extending from the outermost ring to the separate fields in the innermost one, the fields connected by them being larger than the other ones, other equally distributed lines extending from the outermost ring to the third.

5. A society game, comprising a board showing four concentric rings, an annular line in each of the two outer rings and three annular lines in the third ring, counter- or men-fields inserted into all said lines, separate fields located in the fourth or innermost ring, equally distributed radial lines connect-
ing some of the fields in the first, second and third ring with each other, other radial lines connecting only the remaining fields in the third ring with each other.

In testimony whereof I affix my signature.

ARTHUR SPILLING.
